UNITED STATES PATENT OFFICE

2,475,000

SPRAY GUN NOZZLE

Howard Warren Beach, Jr., Montville, N. J., assignor to Eclipse Air Brush Co., Newark, N. J., a corporation of New Jersey

Application February 26, 1947, Serial No. 730,983

2 Claims. (Cl. 299—140.1)

1

This invention relates to improvements in devices for spraying materials such as lacquers, varnishes, paints or semi-pastes, and particularly to so-called spray guns that are designed to discharge a substantially fan-shaped spray stream.

An object of the invention is to provide a novel spray head or nozzle for use in conjunction with spray guns which facilitates effective control of the fan-shaped spray from a minimum narrow fan-spread width to a very wide fan-spread width to suit the particular job at hand. By fan-shaped, I mean flaring or divergent in width but preferably of small depth or thickness.

Another object of the invention is to secure this effective fan-spread control by pneumatic or other gaseous means.

Still other objects are to provide means for increasing the atomization of the spray material along the outer fan edges, to make the device substantially self-cleaning, and to render it more universally adaptable for a larger variety of paints and other spraying materials.

A further object is to provide structure that is mechanically simple, highly efficient in operation, which utilizes a minimum of spraying material and air or gas pressure to accomplish the best atomizing results, and which is capable of use with existing spray guns.

To the accomplishment of the foregoing and such other objects and features as may herein-after appear, this invention consists in the novel method, construction and arrangement of parts hereinafter to be described and then sought to be defined in the appended claims, reference being had to the accompanying drawing forming a part hereof, which shows, merely for the purposes of illustrative disclosure a preferred embodiment of the invention, it being expressly understood, however, that changes may be made in practice within the scope of the claims, without digressing from the inventive idea.

In the drawing wherein similar reference characters denote corresponding parts:

Fig. 1 represents a vertical longitudinal cross-section through a spray gun shown in closed condition to which the novel nozzle or spray head embodying the invention has been applied;

Fig. 2 is a horizontal longitudinal cross-section taken along line 2—2 of Fig. 1 and viewed in the direction of the arrows;

Fig. 3 is an enlarged longitudinal cross-section of the spray head or nozzle and fluid tip taken along line 3—3 of Fig. 4; and

Fig. 4 is a full end elevational view of the nozzle of Fig. 3 viewed from the left thereof.

2

Referring to the drawings, 1 designates the body of the device as a whole, this body including the barrel portion 2 and the handle portion 3, the latter extending downwardly from the barrel portion and inclined slightly to the rear so that the device has somewhat the appearance of an automatic pistol.

Devices of this kind are employed to spray material principally for coating purposes, the material being atomized by air or other gas under pressure. In general the spray gun illustrated has the construction disclosed in Austin H. Downs U. S. Patent No. 2,228,226, granted January 7, 1941. Other types of spray guns, however, may be employed. The material to be sprayed is fed to the point of atomization by pressure and consequently the spray gun has ports, passages and valves for controlling the admission and passage of the pressure fluid, as well as the liquid material and the atomization of the same.

In the embodiment shown, a hose connection 4 to a suitable source of air or other gaseous fluid under pressure is connected at 5 at the bottom of the handle portion 3 to a passageway 6 which extends upwardly through the handle 3 to the air inlet valve chamber 7. This chamber has a valve seat 8 at one end of a distributing chamber 9. A connecting passageway 10 leads from the distributing chamber to a passageway 11 which extends through the barrel towards its nozzle end. A second connecting passageway 12 leads from the distributing chamber 9 to a valve chamber 13. A spring-pressed valve body 14 which is seated normally in closed position on the valve seat 8 is carried in the inlet valve chamber 7. The operating stem 15 of the valve body is engageable by a trigger 16. This trigger is secured pivotally at 17 and when drawn toward the handle 3 operates the stem 15 to unseat the valve 14 from seat 8, thereby opening passageway 11 and valve chamber 13 to fluid pressure.

The valve chamber 13 is connected to a passageway 18 through a valve seat 19. The passageway 18 extends forwardly within the barrel 2 towards its nozzle end. A manually operable adjustable needle valve 20 controls flow of gaseous pressure fluid to the passageway 18 from the valve chamber 13. It may be set to cut-off engagement on the valve seat 19 and be moved off the seat as desired to regulate flow of air or other gaseous pressure fluid to the passageway 18 for purposes presently to be described.

The air passages 11 and 18 extend along the barrel 2 towards its front end and lead to the respective chambers 21, 22. A passageway 23 ex-

tends forwardly from the chamber 21 through the barrel 2 and terminates in the flat outer end face thereof. A passageway 24 extends similarly from the chamber 22 through the barrel 2 and terminates in the flat outer end face thereof at a greater distance from the center than does passageway 23, for a purpose presently to be described. The chambers 21 and 22 are provided to facilitate the boring of the passages 23 and 24 and each is suitably sealed as by a plug 25.

A longitudinal bore 26 is provided in the forward barrel portion, forming a liquid receiving chamber, which in turn is connected to a material supply passage 27. This supply passage 27 extends downwardly through the downward extension 28 of the barrel whose lower portion is screw-threaded at 29 to afford a connection to a suitable source of liquid under pressure.

A fluid tip 30 is secured threadedly in the forward end of bore 26. This tip 30, in the embodiment shown, has a hexagonally or polygonally shaped flange 31 which abuts the flat end of the barrel 2, a cylindrical portion 32 equal in diameter to the inscribed circle of the polygon adjacent the flange 31, a conical portion 33 adjacent the cylindrical portion 32 and a small diameter cylindrical nose 34. Longitudinal slots 35 are provided on the outer surface of the tip 30, preferably being centered with respect to the faces of the polygonal flange 31. A longitudinal bore 36 extends through the tip 30 for its entire length. The inner end 36a of the bore 36 serves as a valve seat for a valve 37 provided on the forward end of a valve rod 38. The valve rod 38 is movable longitudinally in the chamber 28 for seating and unseating of the valve 37 from its seat 38. The rod 38 extends outwardly or rearwardly through a packing gland 39 and to a suitable adjustable coupling for operation by the trigger 16, for example, as described in the aforesaid Downs Patent No. 2,228,226. The spring 40 normally forces the rod 38 to close the valve 37 on seat 36a.

The novel nozzle 42 which is used with the spray gun just described is of the slot type. This nozzle, which I term a "fan slot" nozzle, is of general cylindrical form, being substantially hollow and adapted to be applied over the fluid tip 30 with its inner or bottom edge 43 abutting the flat end face of the barrel 2. The nozzle has a cylindrical passage or cavity 44, constituting the discharge passage, the diameter of said passage being greater than that of said nose 34 of the fluid tip 30. When these parts are assembled the nose 34 is positioned in alignment with said passage 44 with its end spaced from the inner entrance to said passage. The nozzle is formed with a conical passage or cavity 45, which is located rearwardly of said passage 44. When the nozzle and tip are assembled, the conical portion 33 of the tip is spaced from the wall of the conical passage 45. This conical passage 45 is in communication with a cylindrical portion or cavity 46, the diameter of which is greater than that of passage 44 and is substantially the same as that of the cylindrical portion 32 of the fluid tip. The nozzle is also provided with an enlarged cylindrical passage or cavity 47, which communicates with the cylindrical portion 46. The diameter of cavity 47 is large enough to permit free passage to it of air from the outlet end of the barrel passageway 23 but to exclude air from the outlet of barrel passageway 24, for purposes presently described.

The rear face of the nozzle is cut away annularly at 48 and this annular portion overlies the outlet of the barrel passageway 24, so that

when assembled a chamber 48a is provided between the end of the barrel and the nozzle. A pair of gas or air discharge passageways 49, 50 extend through the body of the nozzle 42 from the cutaway portion 48 towards the fan slot 51. These passageways 49, 50 respectively join the oppositely inclined and directed air or gas discharge passageways 52, 53 whose outlet ends are located in the fan slot 51 and substantially at or directly adjacent the opposite ends of the said fan slot. The passageways 52 and 53 are directed so that their axes lie at opposite angles each ranging of from 1° to 10° with a plane perpendicular to the longitudinal axis of the nozzle 42, for example, the plane A—A, which is perpendicular to axis B—B (Fig. 3). The angle of inclination is small and the range of the angular disposition of these passageways is critical because successful operation with inclinations outside of this range is not practical for reasons that will presently appear.

Externally the nozzle 42 has an annular flange 54 providing an annular shoulder 55 for securing the nozzle 42 to the barrel 2 by means of a clamping nut 56 which has a complementary flange 56a to engage the shoulder 55 and screw-threadedly engages an external thread 57 on the tip end of the barrel 2. When the clamping nut 56 is tightened to secure the nozzle 42 to the barrel, it and the cutaway portion 48 of the nozzle define the concentric distributing or chamber 48a for air or gas from the passageway 24 to the passageways 49, 50 and thence to the passageways 52, 53.

The fan slot 51 is concave inwardly from the delivery face of the nozzle and towards the chamber 44. It is to be noted too, that the cylindrical passage 44 in the nozzle 42 extends in the nozzle body beyond the innermost edge of the fan slot 51 and as the slot is less in width than the diameter of the passage or atomizing chamber 44, shoulders 44a are formed, and these shoulders assist in breaking up the liquid as it emerges from the portion 34 of the fluid tip in said atomizing chamber. This chamber 44 is located centrally with respect to the slot 51. Furthermore, the air or gas stream itself is broken up by the numerous abrupt changes of direction it undergoes in passing from the passageway 23 through the passage 47, the slots 35 and the space or clearance between the conical portion 33 of the tip and the inner surface of the nozzle. It is important to note that the air or gas is directed at an angle across the end 34 of the fluid tip and thus breaks up or atomizes the fluid as it leaves the end of the tip and before it enters the passage 44. This breaking up of the air or gas and abrupt changing direction of flow of air or gas across the stream of coating fluid as it emerges from the fluid tip results in complete breaking up and atomization of the coating liquid and its discharge in the form of a finely-divided spray of uniform density. This action also retards the direct flow of coating liquid from the nozzle which would result in an uneven spray of non-uniform density. The air or gas being directed by the shoulders 44a across the stream of coating liquid retards the flow of the same through the nozzle, breaks it up into small particles and prevents its passage through the nozzle as a stream of liquid. This retarding action resulting from what might be termed eddy currents of air or gas is very important and gives effective atomization. It makes the use of a pressure feed cup possible in a device of this character and gives efficient results in the application of these materials.

Such a pressure feed cup is described in the Downs Patent No. 1,706,875.

In operation, it being understood that a source of fluid under pressure is connected to the extension 29, and that a source of air or gas pressure is connected to the connection 4, the operator presses the trigger 16. This immediately opens the valve 14 whereby a supply of air or gas under pressure is admitted into the air or gas distributing chamber 9 and from there to the passages 10, 11, 23 and from thence through the slots 35 and clearances about the fluid tip 34 into the atomizing chamber 44. Likewise, air or gas is admitted to the needle valve chamber 13 through the passageway 12 but since needle valve 20 is closed initially the air or gas is blocked from the passageway 18.

The air or gas from passageway 23 under pressure passes through the slots 35 in the fluid tip 30 and the spaces or clearances between the tip and nozzle 42 and across the end 34 of the tip 30 and then strikes the shoulders 44a of the nozzle, being thereby deflected and then out through the fan slot 51. Since the trigger 16 has not yet moved the valve rod 38, there is no passage of paint or other coating liquid, and this does not occur until air or gas under pressure is flowing through and emerging from the nozzle slot 51. Further movement of the trigger 16 retracts the valve rod 38 unseating valve 37 from its seat 36a. This permits the paint or other coating fluid delivered under pressure to chamber 26 through passageway 27 to pass through the fluid tip bore 36 to its outlet end in nose 34. Then the fluid meets the outrushing current of air or gas under pressure and is completely broken up and atomized and forced out of the fan slot passage 51 in the form of a fan-like sheet of misty fluid material for application as a surface coating. The spread of the emerging fan spray is widest at this time while the needle valve 20 remains closed.

To decrease the fan spread of the spray for accommodation to the surface to be coated, the needle valve 20 is now opened to permit flow of air or gas under pressure from valve chamber 13 through passageways 18, and 24 into annular space 48a and thence through passageways 49 and 50 and the oppositely directed inclined passageways 52, 53 whose respective outlets lie adjacent the opposite sides of the fan slot 51. The jets of air or gas emerging under pressure from these outlets strike the opposite side edges of the fan spray emerging from the fan slot 51 and operate to reduce the fan spread. At the same time they operate to increase the atomization of the spray particles particularly those at the outer edges of the fan spray. The degree of reduction in fan spread effected by these oppositely directed jets from the passageways 52 and 53 depends upon their volume and velocity and these are controlled as desired by regulation of the needle valve 20. If the latter is wide open, minimum fan spray spread is effected. If the needle valve 20 is entirely closed, the fan spray spread is at a maximum.

In an actual test of a construction embodying the invention, utilizing a fan slot 51 approximately $\frac{5}{8}$ " long held approximately 10" from a spray surface, and utilizing an air dry enamel as the coating fluid under pressure of 30 pounds per square inch and an atomizing air pressure of 35 pounds per square inch, with the needle valve 20 closed, the maximum effective fan spread width was approximately $15\frac{1}{2}$ ". With the needle valve

20 fully opened, under the same pressure conditions, the minimum effective fan spread was approximately $1\frac{3}{4}$ " to 2". In other words, a reduction in width ranging from approximately $\frac{1}{8}$ to almost $\frac{1}{9}$ the maximum fan spread width is possible.

Under similar conditions and with the same spray gun, nozzles having angular disposition of the jet directions above the critical range of 1° to 10° specified herein are found to provide much less possible reduction. For example, in one device tested under similar conditions of pressure wherein the angular disposition of the jets was approximately 45° , the maximum effective fan spread was found to be approximately $12\frac{1}{4}$ " and the minimum fan spread was found to be approximately $6\frac{3}{4}$ ". In other words, the maximum reduction in width effected was less than $\frac{1}{2}$ the maximum fan spread.

20 When the direction of the jets from passages 52, 53 lie below 1° , the device it has been found becomes substantially inoperative with valve 20 opened because of cut-off effects produced by the oppositely directed jets of air under high pressure from the passageways 52, 53. Any angular disposition of the jet passages 52 and 53 of more than 10° with a plane normal to the longitudinal axis of the nozzle results in insufficient narrowing effects upon the fan spread.

30 When the trigger 16 is released by the operator, in the spray gun shown, coating fluid cut-off occurs with the immediate closing of needle valve 37. This occurs prior to air cut-off effected by the 35 later closing of the air valve 14. As a result the air or gas jets from passageways 52 and 53 as well as the atomizing air or gas jet emerging from the fan slot 51 continue momentarily after 40 cessation of fluid flow and serve to blow out and whip off residual coating fluid material about the fan slot 51 and the fluid tip nose 34. Likewise, the earlier cut-off of the coating fluid prevents drip. The device is thus largely self-cleaning.

The respective parts of the spray gun and particularly the fluid tip 30 and the nozzle 42 are 45 made of metal or other suitable substances which may be machined and tooled to precise dimensions for the purposes of securing effective fan spread control and to have sharp outside edges to prevent accumulation of fluid and to assist in the self-cleaning actions described.

While a specific embodiment of the invention has been disclosed, variations in structural detail are possible and are contemplated within the 55 scope of the claims. There is no intention, therefore, of limitation to the exact details shown and described.

What is claimed is:

1. A spray head including a discharge passage 60 with an outlet end in said head, a fan slot extending from said outlet end and opening to the outside of said head for ejecting a fan spray, and fluid passageways having outlet ends positioned in the opposed end walls of said slot so that their axes are oppositely inclined at angles limited to from about 1° to 10° to a plane perpendicular to the axis of said discharge passage's outlet end, and intersect beyond the latter, said fluid passageways being adapted to be supplied 65 with fluid under pressure for restricting the width of said spray.

2. A spray head as defined by claim 1 with said discharge passage cylindrical in shape and extending partially into said fan slot and of greater 70 diameter than the latter's width, said opposed end 75

walls of said fan slot flaring arcuately from said discharge passage's outlet end with a radius proportioned respecting the latter's diameter to make said opposed end walls overhang said outlet end sufficiently to accommodate said fluid passageways' outlet ends positioned as defined.
